DOLL CONSTRUCTION

Matteo De Cesare, Newark, N. J., assignor to
 Samuel Kalner and Karl Ohlbaum, New York,
 N. Y.

Application August 8, 1933, Serial No. 684,163

17 Claims. (Cl. 46—169)

This invention relates to doll construction and is particularly directed to a doll's eye set and means for mounting the same on the doll's head.

An object of this invention is to provide in doll construction wherein doll's eyes are rotatably received within the eye sockets of the doll's head, improved means for yieldingly retaining said eyes for rotation within said sockets and means for preventing the doll's eyes from being pushed out of the sockets.

Another object of this invention is to provide in doll construction of the character described wherein doll's eyes are rotatably received within the eye sockets of the doll's head, improved means for adjusting the position of the eyes within the sockets to insure free rotation of the eyes with respect to said sockets.

A further object of this invention is to provide an improved doll's eye set of practical construction, which may be easily manufactured and assembled.

A still further object of this invention is to provide a strong, rugged doll construction of the character described, which shall be comparatively inexpensive to manufacture, easy to assemble and install within the doll's head, and which shall nevertheless be positive and smooth in operation, and attractive and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a cross-sectional elevational view of a doll's head provided with doll's eye construction embodying the invention;

Fig. 2 is a rear elevational view of the inside of the doll's head;

Fig. 3 is a cross-sectional view taken on line 3—3 of Fig. 1;

Fig. 4 is a cross-sectional view taken on line 4—4 of Fig. 1;

Fig. 5 is a cross-sectional, elevational view of doll's eye structure embodying the invention and illustrating a modified construction; and

Fig. 6 is a cross-sectional view taken on line 6—6 of Fig. 5.

Referring now in detail to the drawing, 10

designates a doll's head comprising a front portion 11 and a rear portion 12 secured together in the usual manner. The front portion 11 is provided with eye sockets 13 for reception of the doll's eyes. The rear edge of the front portion 11 is provided with notches 15 on opposite sides thereof at a level above the eyes, receiving the ends of a horizontal rod 16 fixed in position when the head parts 11 and 12 are attached together.

Attached to the rod 16 and disposed at right angles thereto is a horizontal member 17 having parallel flat portions 18, the adjacent ends whereof are formed with openings receiving the rod 16 therethrough. The parallel portions 18 are interconnected by a U-shaped portion 20 received within the notch 21 formed on the interior surface of the head portion 11 somewhat above the nose. The portions 18 may be fixed to the bar 16 in any suitable manner, and as shown in the drawing, are flat and disposed in vertical parallel planes forming a groove or slot 22 therebetween. Attached to the flat portions 18 adjacent the U-shaped portion 20 thereof is a transverse pin 24 parallel to the rod 16. Slidably mounted on the portions 18 is a sleeve 26 preferably made of a single piece of sheet metal and having a top, bottom and side portion, and extending downwardly and forwardly from the bottom portion thereof is a finger 27. One of the flat portions 18 is formed with a notch 28 and the bottom portion of the sleeve 26 is formed with a tab 29 adapted to be bent into said notch. The sleeve 26 is preferably made of metal which is sufficiently thin to be bent by an instrument.

Thus, as will be explained in greater detail hereinafter, the sleeve 26 may be pushed forwardly and the tab 29 pressed into the notch 28 to hold the sleeve against further sliding movement.

Pivotedly mounted on the pin 24 and extending through groove or slot 22 is a member 30 preferably made of sheet metal and comprising a flat portion 31 and a pair of integral flat parallel hooks 33 extending at right angles thereto and received over said pin 24. Extending from the lower end of said portion 31 is a humped or channel-shaped portion 34 located at about the level of the eye sockets 13. Extending from the humped portion 34 is a flat portion 35 aligned with the portion 31. Attached to the upper end of the portion 31 is a spring 37 curved upwardly and rearwardly with the free end of said spring contacting the inner surface of the top of the doll's head. The spring 37 may have a coil and tends to pivot the member 30 clockwise about the 55

pin 24 for moving the humped portion 34 toward the eye sockets.

Mounted on the member 30 in the manner hereinafter described, is a doll's eye set 40 comprising a member 41 made of sheet metal, to the lower end of which is attached a weighted member 42. The upper end of the member 40 is formed with a pair of parallel ears 43 having aligned openings 44 receiving therethrough a shaft or axle 45, extending through said ears. The shaft 45 may be made of round stock; and mounted on the extending portions thereof are semi-spherical doll's eyes 46, each having diametrically disposed openings receiving said axle therethrough. The ends of the axle 45 may be upset for retaining the doll's eyes thereon.

For preventing rotation of the doll's eyes with respect to said axle, there is attached to the rear of the member 41 at the upper end of the latter, a member 49 made of sheet metal and having a clip 50 engaging the upper edge of the member 41 between the ears 43. The member 41 is further formed with a slot 52 receiving therethrough a clip 53 extending from the lower edge of said member 49. The member 49 is formed with a pair of flat co-planar wings 54 contacting the rear edges 55 of the doll's eyes 46. Thus, as the member 41 swings the doll's eyes swing therewith whereby the entire doll's eye set 40 moves as a unitary member. The doll's eye set may be mounted on the member 30 by passing the portion 35 of said member between the axle and the member 41 and between the ears 43. The central portion of the axle is thus received within the humped portion 34.

In assembling the device, the sleeve 26 may be first mounted on the member 17 and the rod 16 passed through the openings in the portions 18 and fixed thereto. The members 16 and 17 are then placed in position on the head portion 11 to which the head portion 12 is then attached, thus firmly securing the members 16 and 17 within the head. The sleeve 26 is retained at the rear of the flat portions 18. The eye set 40 is then assembled with the member 30 and passed through the neck of the doll's head. The spring 37 is fed into the slot 22 between the pin 24 and the sleeve 26. The hook portions 33 are then engaged with the pin 24 whereby the spring 37 presses the doll's eyes into the sockets. To prevent the eyes from being poked out of the sockets, the sleeve 26 is then pushed forwardly until the tab 29 is aligned with the notch 28. By inserting an instrument through the neck of the doll's head, the tab 29 may then be pressed into the notch.

As shown in Fig. 1 of the drawing, the tip of the finger 27 is spaced from the member 30. However, should the eyes be pressed rearwardly into the sockets, the member 30 will contact the finger 27 to prevent the eye set 40 from falling out of position.

It will now be understood that the doll may be moved from sitting to lying position for causing swinging movement of the eye set 40 and rotation 65 of the doll's eyes from sleeping to waking position.

In Figs. 5 and 6 is shown a modified construction wherein there is pivotally mounted on the pin 24 a member 60 preferably made of a single strip of bent and shaped metal and having a looped portion 61 rotatably receiving said pin. The member 60 may likewise be provided with a humped portion 62 for receiving the axle of the eye set 40. Extending rearwardly from the looped portion 61 is a portion 63 formed with a screw

threaded opening 64. Attached to the parallel flat portions 18 and disposed adjacent the rod 16 is a yoke 65 overlying the screw threaded opening 64 in the portion 63. A screw 66 screwed to the opening 64 is adapted to engage the underside of the yoke 65. Thus, by turning the screw 66, the member 60 may be swung for positioning the doll's eyes 46 within the sockets of the doll's head. With such adjustment, the doll's eyes may be disposed within the sockets in position for permitting 10 rotation of the eye set without causing a frictional binding of the eyes. Free rotation of the eyes may thus be obtained by proper adjustment of the screw.

The wall 18 formed with the notch 28 may be 15 provided with a plurality of such notches to permit adjustment of the position of the sleeve 26. Furthermore the tab 29 may be constructed to snap into the notch 28.

It will thus be seen that there is provided a 20 device in which the several objects of this invention are achieved, and which is well adapted to meet the conditions of practical use.

As various possible embodiments might be made of the above invention, and as various changes 25 might be made in the embodiments set forth above, it is to be understood that all matter herein set forth or shown in the accompanying drawing is to be interpreted as illustrative and not in a limiting sense.

Having thus described my invention, I claim as new and desire to secure by Letters Patents:

1. In doll construction, a doll's head formed with a pair of eye sockets, a cross rod attached to the sides of the head, a member attached at 35 one end thereof to the front of the head above the nose and at the other end thereof to the mid-portion of said rod, a transverse pin fixed to said member, a member pivoted on said pin, an axle mounted on said pivoted member, and doll's eyes 40 mounted on said axle and received within said sockets.

2. In doll construction, a doll's head formed with a pair of eye sockets, a cross rod attached to the sides of the head, a member connected 45 at one end thereof to the front of the head above the nose and at the other end thereof to the mid-portion of said rod, said member having parallel portions, a transverse pin fixed to said parallel portions, a member pivoted on said pin and received between said parallel portions, an axle 50 mounted on said pivoted member, doll's eyes mounted on said axle and received within said sockets, and spring means for causing rotation of said pivoted member.

3. In doll construction, a doll's head formed with a pair of eye sockets, a cross rod attached to the sides of the head, a member connected at one end thereof to the front of the head above the nose and at the other end thereof to the mid-portion 60 of said rod, said member having flat parallel portions, a transverse pin fixed to the parallel portion of said member, a member made of a single piece of metal pivoted on said pin and received between said parallel portions, an axle 65 mounted on said last mentioned member, doll's eyes mounted on said axle and received within said sockets, and spring means for causing rotation of said last mentioned member.

4. In doll construction, a doll's head formed 70 with a pair of eye sockets, a cross rod attached to the sides of the head, a member connected at one end thereof to the front of the head above the nose and at the other end thereof to the mid-portion of said rod, a transverse pin fixed to said 75

member, and a member pivoted on said pin, an axle mounted on said last mentioned member, doll's eyes mounted on said axle and received within said sockets, and screw threaded means for adjusting the position of said last mentioned member.

5. In doll construction, a doll's head formed with a pair of eye sockets, a cross rod attached to the sides of the head, a member connected at one 10 end thereof to the front of the head above the nose and at the other end thereof to the mid portion of said rod, said member having flat parallel portions, a transverse pin fixed to the parallel portions of said member, a member pivoted to said 15 pin and received between said parallel portions, an axle mounted on said last mentioned member, doll's eyes mounted on said axle and received within said sockets, and a spring fixed to said pivoted member and engaging the inner surface of 20 said head for pressing said eyes into said sockets.

6. In doll construction, a doll's head formed with a pair of eye sockets, a cross rod attached to the sides of the head, a member connected at one 25 end thereof to the front of the head at the nose and at the other end thereof to the mid portion of said rod, said member having flat parallel portions, a transverse pin fixed to the parallel portions of said member, a member pivoted to said 30 pin and received within said parallel portions, an axle mounted on said last mentioned member, doll's eyes mounted on said axle and received within said sockets, a spring fixed to said pivoted member and engaging the inner surface of said head for pressing said eyes into said sockets, and 35 a sleeve slidably mounted on said parallel portions and having a finger extension, said pivoted member being movable into contact with said finger extension.

7. In doll construction, a doll's head formed with a pair of eye sockets, a cross rod attached to the sides of the head, a member connected at one 40 end thereof to the front of the head and at the other end thereof to the mid portion of said rod, said member having flat parallel portions, a transverse pin fixed to the parallel portions of said member, a member pivoted to said pin and received within said parallel portions, an axle mounted on said last mentioned member, doll's eyes mounted on said axle and received within said 45 sockets, a spring fixed to said pivoted member and engaging the inner surface of said head for pressing said eyes into said sockets, and a sleeve slidably mounted on said parallel portions and having a finger extension, said pivoted member being movable into contact with said finger extension, one of said flat portions being formed with a notch and said sleeve having a tab adapted to be bent into said notch to limit sliding movement thereof.

8. In doll construction, a doll's head formed with a pair of eye sockets, a member fixed within 50 said head, a member pivoted to said first member, a doll's eye set mounted on said pivoted member and having doll's eyes adapted to be received within said sockets, a member slidably mounted on said 55 first member and adapted to limit rotary movement of said pivoted member, said first member having a notch and said slidably mounted member having a tab extending into said notch for retaining said slidably mounted member against 60 sliding movement.

9. In a doll construction, a doll's head formed with a pair of eye sockets, a cross rod attached to the sides of the head, a member attached at one 65 end thereof to the front of the head above the nose and at the other end thereof to the mid por-

tion of said rod, a transverse pin fixed to said member, a member pivoted on said pin, screw threaded means for rotating said member, an axle mounted on said pivoted member and doll's eyes mounted on said axle and received within 5 said sockets.

10. In a doll construction, a doll's head formed with a pair of eye sockets, a cross rod attached to the sides of the head, a member having parallel portions attached at one end thereof to the front 10 of the head above the nose and at the other end thereof to the mid portion of said rod, a transverse pin fixed to said parallel portions, a yoke attached to said parallel portions, a member rotatably mounted on said pin, an axle mounted on 15 said rotatable member, doll's eyes mounted on said axle and received within said sockets, and a screw screwed to said member and engaging said yoke.

11. In combination with a doll's head having 20 eye sockets, a horizontal rod within said head having the ends thereof engaging the sides of the doll's head, a rail-like member within the doll's head extending from front to rear and having the front end thereof engaging the front of the doll's 25 head and the rear thereof engaging said rod, a pair of doll's eyes on an axle received within the sockets of the doll's head, resilient means for yieldingly pressing the eyes into said sockets, and means on said rail-like member to limit rearward 30 movement of said eyes.

12. In combination with a doll's head, a horizontal rod within said head having the ends thereof engaging the sides of the doll's head, a rail-like member within said doll's head comprising 35 a pair of parallel portions interconnected at the front, the interconnecting portion engaging the front of the doll's head, the rear ends of said parallel portions engaging said rod, a member 40 slidably mounted on said rail-like member, a pair of doll's eyes mounted on an axle and received within the sockets of the doll's head, resilient means for yieldingly pressing said eyes into said 45 sockets, and means on said slidably mounted member serving as a stop to limit rearward movement of said eyes out of said sockets.

13. In combination with a doll's head provided with a pair of sockets, a member within the head extending from front to rear, a member slidably mounted on said first member, an axle having 50 doll's eyes received within the sockets of the doll's head, resilient means for pressing the doll's eyes within said sockets, and means on said slidably mounted member serving as a stop to limit rearward movement of the eyes out of said sockets. 55

14. In combination with a doll's head provided with a pair of sockets, a member within the head extending from front to rear, a member slidably mounted on said first member, an axle having doll's eyes received within the sockets of the doll's 60 head, resilient means for pressing the doll's eyes within said sockets, and means on said slidably mounted member serving as a stop to limit rearward movement of the eyes out of said sockets, said first member being formed with a notch and 65 said slidably mounted member having a tab received within said notch to retain said slidably mounted member against sliding movement.

15. In combination with a doll's head having a pair of eye sockets, a member fixed within said 70 head and extending from front to rear thereof and having a pair of parallel walls, a member slidably mounted on said first member, a pair of doll's eyes mounted on an axle and received within said eye sockets, means between said walls for 75

yieldingly pressing said eyes into said sockets, and stop means on said slidably mounted member to limit rearward movement of said eyes and axle.

16. In combination with a doll's head having a pair of eye sockets, a member fixed within said head and extending from front to rear thereof and having a pair of parallel walls, a member slidably mounted on said first member, a pair of doll's eyes mounted on an axle and received within said eye sockets, means disposed between said walls for yieldingly pressing said eyes into said sockets, stop means on said slidably mounted member to limit rearward movement of said eyes and axle, and means for retaining said slidably mounted member against sliding movement on said first member, said last means including an opening in at least one of said parallel walls, and a tab on said slidably mounted member received within said opening.

17. In combination with a doll's head having a pair of eye sockets, a horizontal rod within said

head having the ends thereof engaging the sides of the doll's head, a rail-like member within said doll's head comprising a pair of parallel portions interconnected at the front, the front of the doll's head being formed with a recess receiving the interconnecting portion of said rail-like member, the rear ends of said parallel portions being formed with aligned openings receiving said rod therethrough, a pair of doll's eyes mounted on an axle, and received within the sockets of the doll's head, resilient means including a member extending between said parallel portions for yieldingly pressing said eyes into said sockets, a member slidably mounted on said rail-like member, serving as a stop to limit rearward movement of said eyes, said slidably mounted member being formed with a tab and one of said parallel portions being formed with a cut away portion receiving said tab to hold said slidably mounted member against sliding movement.

MATTEO DE CESARE.

20
